UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

METHOD OF TREATING HYDROCARBONS.

Original application filed November 18, 1914, Serial No. 872,698. Divided and this application filed February 28, 1921. Serial No. 448,735.

To all whom it may concern:

Be it known that I, CARBON P. DUBBS, a citizen of the United States, residing in the city of Wilmette, county of Cook, and 5 State of Illinois, have invented certain new and useful Improvements in Methods of Treating Hydrocarbons, of which the following is a specification.

This application is a division of an original 10 application filed by me in the United States Patent Office, Serial No. 872,698, filed Nov. 18, 1914.

The invention relates to a method of treating hydrocarbons and refers more particularly to the cracking of petroleum oils and the specific purpose of the present application is more particularly directed to the method of condensing certain of the cracked vapors.

20 By means of the present invention the generated vapors may be first subjected to a definitely controlled reflux condensing action in which the temperature of the reflux condenser is positively controlled during 25 any stage of the cracking operation whereby a distillate of the desired character is obtained; to provide a process in which the vapors when subjected to a reflux condensing action are caused to travel alternately 30 in substantially horizontal and then vertical directions; to provide a process in which the vapors may be subjected to the reflux condensing action of cooling fluids whereby the temperature of the reflux condenser is 35 controlled; to provide a novel form of apparatus to carry out the above described method and in general to provide improvements of the character referred to.

In the drawings:

40 Fig. 1 is a somewhat diagrammatic view, partly in side elevation, and partly in vertical cross section of the apparatus.

Fig. 2 is a sectional view through one of the baffle plate tubes.

45 Referring more particularly to the drawings, 1 designates the still mounted on furnace supports 2, provided with an inlet filling valve-controlled pipe 3 and liquid valve-controlled drawoff pipe 4. Pyrometer wells 5, safety pressure valve 6 are also provided. Extending down into the still is a steam pipe 7 connected at its lower end with a horizontally extending perforated pipe 8. The pipe 7 is provided with pressure gauge

9, throttle valve 10 and pyrometer 11. The pipe 7 connects to steam supply pipe 12 in which may be interposed a pump 13 to increase the steam pressure. The steam may be superheated by means of superheater 14 and steam coil contained therein controlled by throttle valves 15 and 16. The main line 12 is also provided with throttle valves 17 and 18.

A vertical vapor outlet pipe 19 extends into the still, below the top of the latter and to the upper end of the pipe 19 is connected a reflux condenser 22 enclosed by a cooling jacket 21. This jacket 21 receives water or another temperature controlling medium which circulates through said jacket, and by means of which the temperature of the reflux condenser is controlled. The cooling fluid that passes through this jacket maintains the reflux condenser at such a temperature as to condense and return to the still those vapors which do not have a low enough boiling point, that is to say, when making gasoline from heavier hydrocarbons, substantially the gasoline-like vapors are separated in this condenser from the heavier less-volatile vapors, which heavier vapors as reflux condensate are re-cracked. The gasoline-like vapors are recovered after a final condensation as a volatile oil containing substantial quantities of gasoline, which oil is generally known in the trade as pressure distillate, the product from all cracking plants. It is to be particularly noted that the reflux condenser is so arranged to provide alternate, horizontal and vertical passages through which the vapors are compelled to travel thus causing a continued back and forth movement in horizontal and vertical lines, of the vapors. The vapors which are condensed will fall back into the still 1.

I also provide a means for cutting out the reflux condenser through the by-pass pipe 23 or 24, the various pipes being controlled by throttle valves 25, 26 and 27. The valve 28 is also provided preferably interposed in the pipe 23. To the left of the valve 28 is an upright 29 controlled by throttle valve 31 and leading to the air condenser 30. The pipe 34 leads from the upper end of the air condenser 30 and is controlled by throttle valve 35. Likewise, a pipe leads from the upper end of the reflux

condenser 22 and is controlled by throttle valve 36. Delivery pipe 32 controlled by throttle valve 38 leads to the water condenser coil 20 seated in condenser box 20'. To the outlet side of the condenser is connected a cross 39, one end of which is connected to a pipe controlled by the weighted valve 40, the upper end of which is connected to a gas outlet 41 controlled by valve 42. A branch 43 connected to vacuum pump 44 and controlled by valve 45 is also provided, whereby the system may be maintained under either pressure or vacuum. The pipe 24 is controlled by valve 37. Referring back to the air condenser 30, it is provided with a series of aerial baffles 48, mounted on suitable open-ended air pipes extending through the walls of the condensers 30 and controlled by the air valves 47.

If desired, steam may be introduced into the pipe 24 through lines 49 and 50 having throttle valve 51, pressure gauge 52 and connected to the perforated pipe 53 located in the pipe 24, which is surrounded by a furnace 54 which furnace is heated by suitable burners. Perforated pipe 53 has perforations 56 which may be controlled by the rotary sleeve valve operating from the handle 58. If desired, a pyrometer may be inserted in the pipe 24 at the point marked 55. Similarly, the perforations 59 in the pipe 8 may be controlled by the rotary sleeve valve 60 having handle 61.

In the operation of the process a superatmospheric pressure may be maintained throughout the system. During one operation, a body of oil is introduced to the still 1, and this oil is heated to a temperature of say 800° F., the generated vapors serving to maintain a pressure throughout the system by valves, which will be later described. The vapors from the vapor space in the still may pass through the outlet pipe 19 into the reflux condenser 22, in which condenser their path of travel is obstructed and the passage confined or restricted, the uncondensed vapors from the reflux condenser passing through the pipe 33, through the open valve 36, the pipe 32, the open valve 38, and into the water condenser 20 disposed within the receptacle 20'. While passing through this water condenser, the vapors are condensed under a superatmospheric pressure, and the pressure distillate is collected in the receiver communicating with the condenser. The pressure is maintained on the condenser, and on the entire system, including the reflux condenser 22, by means of the valves 42 and 45. The reflux condensate produced in the reflux condenser 22 returns to the still 1, where it is retreated by dropping back through the line 19. It will be appreciated that when the process is operated in the manner hereinbefore de-

scribed, only the reflux condenser 22 is being used, and the pipes 24, 23, 29, and the condenser 30 are cut out of the system, thereby permitting the vapors to pass directly from the reflux condenser through lines 33 and 32 to the final water condenser. Obviously, by a proper manipulation of the various valves hereinbefore referred to, the passage of the vapors can be so diverted as to pass through the different pipes or conduits, and the reflux condenser 22 can be by-passed when desired.

A process may also be operated as follows: The reflux condenser 22 may be cut out of the system, and only the condenser 30 used, in which case, the valves 26, 27, 28 and 36 will be closed and the valves 25, 31, 35 and 38 opened. The same pressure as heretofore mentioned may be maintained on the system.

The subject matter claimed in this application relates specifically to the treatment of vapors in the reflux condenser 22, the temperature of which condenser is controlled through the agency of the controlling medium, such as water, whereby the insufficiently cracked vapors are separated from the gasoline-like vapors by condensing said heavier vapors through their retarded flow through the reflux condenser, without condensing the lighter vapors. The heavier condensed vapors are returned to the still for retreatment, while the vapors pass off to a condenser for condensation and collection.

I claim as my invention:

1. The process of producing gasoline-like products from heavier hydrocarbons of a boiling point higher than gasoline, consisting in subjecting the heavier hydrocarbons to a cracking temperature while in a still to decompose the same, in permitting an expansion of generated vapors in a suitable vapor space, in passing the vapors from said vapor space through a passageway to a reflux condenser located away from the still, in causing a retarded flow of the vapors in a restricted stream through said reflux condenser, in separating the heavier insufficiently cracked vapors from the gasoline-like vapors by condensing said substantially heavier vapors during their retarded flow through the reflux condenser without substantially condensing the gasoline-like vapors, by maintaining the temperature of the reflux condenser such as to condense the vapors that do not have a sufficiently low boiling point by the application of a temperature controlling medium to said reflux condenser, in recracking the reflux condensate, in discharging the uncondensed gasoline-like vapors from the reflux condenser to a final condenser without again admitting said vapors to the cracking still, in collecting the condensed gasoline-

like oil, and in maintaining a superatmospheric pressure on the oil undergoing distillation in the still, and on the vapors while in the vapor space and during their retarded travel through the reflux condenser and while in the final condenser.

2. The process of producing gasoline-like products from heavier hydrocarbons of a boiling point higher than gasoline, consisting in subjecting the heavier hydrocarbons to a cracking temperature while in a still to decompose the same, in permitting an expansion of generated vapors in a suitable vapor space, in passing the vapors from said vapor space through a passageway to a reflux condenser located away from the still, in causing a retarded flow of the vapors in a restricted stream through said reflux condenser, in separating the heavier insufficiently cracked vapors from the gasoline-like vapors by condensing said substantially heavier vapors during their retarded flow through the reflux condenser without substantially condensing the gasoline-like vapors, by maintaining the temperature of the reflux condenser such as to condense the vapors that do not have a sufficiently low boiling point by the application of a temperature controlling medium to said reflux condenser, in recracking the reflux condensate, in discharging uncondensed gasoline-like vapors from the reflux condenser to a final condenser without again admitting said vapors to the cracking still, in collecting the condensed gasoline-like oil, and in maintaining a superatmospheric pressure on the oil undergoing distillation in the still and on the vapors while in the

vapor space and during their retarded travel through the reflux condenser.

3. A process of producing gasoline-like products from heavier hydrocarbons of a boiling point higher than gasoline consisting in subjecting the heavier hydrocarbons to a cracking temperature while in a still to decompose the same, in permitting an expansion of generated vapors in a suitable vapor space, in passing the vapors from said vapor space through a passageway to a reflux condenser located away from the still, in causing a retarded flow of the vapors in a confined stream through said reflux condenser, in separating the heavier insufficiently cracked vapors from the gasoline-like vapors by condensing said substantially heavier vapors during their retarded flow through the reflux condenser without substantially condensing the gasoline-like vapors, by maintaining the temperature of the reflux condenser such as to condense those vapors which do not have a sufficiently low boiling point by the application of a temperature controlling medium to the reflux condenser, in maintaining a superatmospheric vapor pressure on the oil during distillation, and on the vapors in the vapor space and in the reflux condenser, in recracking the reflux condensate, in discharging uncondensed gasoline-like vapors from the reflux condenser to a final condenser without again admitting said vapors to the cracking still, and in collecting the condensed gasoline-like oil from said final condenser.

CARBON P. DUBBS.
